R. L. McGEHEE

COTTON PICKER

Filed Feb. 3, 1923

UNITED STATES PATENT OFFICE.

ROBERT L. McGEHEE, OF NEW YORK, N. Y.

COTTON PICKER.

Application filed February 3, 1923. Serial No. 616,799.

To all whom it may concern:

Be it known that I, ROBERT L. McGEHEE, a citizen of the United States, residing at New York city, New York, have invented a certain new and useful Improvement in Cotton Pickers, of which the following is a clear, full, and exact description.

This invention relates to cotton pickers, and particularly to cotton picker heads of the type shown in U. S. Letters Patent to Ira E. McGehee, No. 1,872,711, granted March 29, 1921, a general object of the invention being to improve the picker finger construction and the mechanism for effecting the picking action of the finger in cotton pickers of this type.

Cotton picking mechanism of the type disclosed in Letters Patent above identified has proved in actual use not only to be a great labor saver, but also to effect a marked increase in the capacity of the operator thereof, without the drawbacks hitherto experienced in the mechanical picking of cotton, such as the picking of leaves, sticks, bolls, etc. In the operation of this mechanism, as pointed out in the Letters Patent, it is desirable that the picker fingers reciprocate at comparatively high speed. The fingers not only reciprocate but the picking ends thereof oscillate, these ends moving into closed position at the end of the outward stroke and moving into open position at the end of the inward stroke.

In view of the high speed at which these picker fingers operate, it is important and essential that they be so constructed and arranged that their operation shall be such as to produce a minimum of wear, thereby avoiding the necessity for frequent replacement. In the construction illustrated in the patent above identified, the oscillation of the finger at the end of each stroke is effected through the inertia of a weight attached thereto, the inertia of the weight operating as the reciprocating part of the finger comes to rest to cause the oscillating part thereof to oscillate on its pivotal connection with the part that only reciprocates. The amount of this oscillation is limited by stops.

Furthermore, in the construction shown in the Letters Patent, the weight, through the inertia of which the finger end is caused to oscillate, also partakes of the oscillating movement of the finger end, and the stop which determines the inward movement of

the finger end is so located that the weight first travels with the finger in its reciprocating travel and then travels with the oscillating end of the finger through its path of oscillation, being stopped at the end of its oscillating travel by a stop which is between the weight and the pivot on which the finger oscillates.

It has been found in practice that by reason of this change in direction of the movement of the weight and the stopping of the weight by a stop thus located, the pivotal bearing of the finger is subjected to considerable wear. An object of the present invention is so to construct and arrange the parts as to reduce this wear to a minimum.

The invention also aims to insure a more positive oscillation of the picking end of the finger by avoiding a substantial change in the direction of the movement of the weight while the weight is operating to effect oscillation of the finger end, particularly the movement into picking position.

Other objects and important features of the invention will appear from the following description and claims when considered in connection with the accompanying drawings, in which

Fig. 1 is a side elevation, partly in section, of a cotton picker head embodying the present invention;

Fig. 2 is an enlarged detail elevation of one of the fingers removed from the head;

Fig. 3 is a section through the finger and its guide on the line 3—3 of Fig. 1;

Fig. 4 is a section of the crank pin or pitman connection on the line 4—4 of Fig. 1;

Fig. 5 is an enlarged perspective of the end of the finger showing the lateral guards which prevent the picking of pods, leaves, sticks and other undesirable material;

Fig. 6 shows a modification of the finger construction;

Fig. 7 is a plan view of the construction shown in Fig. 6;

Fig. 8 illustrates a modified tooth construction for the oscillating ends of the fingers;

Fig. 9 is a detail side elevation of a further modification showing still another means of operating the finger through the inertia of a weight, which embodies the present invention; and

Fig. 10 is a plan view of the mechanism shown in Fig. 9.

The cotton picking mechanism herein

shown, like that shown in the Letters Patent hereinabove identified, comprises a series of guides 2 carried at the forward end of a tube 4 through which the picked cotton passes, preferably into a bag (not shown) attached to the flange 6 at the rear end of this tube. Each of the fingers, as in the prior construction, is partly supported upon the outer surface of the tube 4 and partly by the guides 2 which, as shown in Fig. 3, guide and support the finger through the weight 8, the weight being of sufficient width so that it rides in the guide and carries the finger suspended through the opening in the bottom of the guide.

In the form of the finger and weight construction shown in Figs. 1 to 4 inclusive, the oscillating part 10 of the finger embraces the reciprocating part 12 and has a pivotal connection therewith at 14. The reciprocating part 12 of the finger is provided at its outer end with a stop portion 15 which is also embraced by a bellcrank upward extension 16 of the part 10, the whole being received within the rectangular opening in the weight 8.

The length of the rectangular opening in the weight 8 is so proportioned to the length of the stop 14 that the lost motion provided will be sufficient to permit the weight 8 to effect the oscillation of the part 10 between its extreme limits of movement, the extension 16 on the part 10 having an easy working fit within the opening in the weight 8 with substantially no lost motion, whereby the movement of the weight 8 is directly transmitted to the oscillating extension 10 on the finger. The weight is preferably confined upon the reciprocating part of the finger by overhanging projections 20 which may be attached to the finger or, as shown in Fig. 9, formed by bending laterally to opposite sides integral portions of the finger.

In the construction shown in Figs. 9 and 10, a weight 22 is shown which is formed with a crossbar 24 connecting two side members, this crossbar lying between upward extensions or bell-crank arms 26 on the oscillating part of the finger and traveling between stops 28 and 30 on the reciprocating part 12 of the finger, which stops have their upper ends bent laterally in opposite directions to overhang the side members of the weight. This construction also gives a lost motion connection between the weight and the reciprocating part 12 of the finger sufficient to effect the oscillation of the oscillating part 10 of the finger.

In Figs. 6 and 7 of the drawing is shown still another modification in which the weight is integral with the oscillating part 32 of the finger, this part differing somewhat in construction from the oscillating parts described above in this respect, the up-

wardly extending part or bell-crank arm of the oscillating part 32 being made of sufficient weight to serve the purpose of the separate weight in the other constructions. In the construction shown in Figs. 6 and 7 a pivot 34 extending between the two parts of the oscillating member 32 which embrace the reciprocating part 12 of the finger carries a roller 36 which moves between the ends of an arc-shaped slot 38 in the reciprocating part 12 of the finger, these ends serving to limit the oscillation of the part 32 and to provide the necessary lost motion during the reciprocating and the oscillating part of the finger to permit the weighted upper part of the oscillating part 32 to effect the oscillation thereof at each end of the reciprocating movement of the part 12.

In Fig. 5 is shown the construction of the lateral guards 40 which project slightly beyond the teeth 42 at the end of the finger, these guards serving to prevent these teeth from engaging the pods, sticks and similar material which otherwise would be picked with the cotton, and to confine the activity of the fingers to the picking of the fibre. These guards are very effective for this purpose.

Like the cotton picker head shown in the Letters Patent above referred to, the illustrated head is provided with a handle 44 by which it may be carried and which has in its forward end the switch buttons 46 and 48 controlling through wires 50 and 52 the starting and stopping of an electric motor, not shown, usually carried upon the back of the operator, which motor through a flexible shaft, also not shown, is connected to the shaft 54 of a bevelled pinion 56, through which driving of the mechanism for reciprocating the fingers is effected. This mechanism comprises a series of intergeared bevelled gears 57 arranged as shown in the Letters Patent hereinabove identified, except that instead of having the bearings upon the tube as shown in the Letters Patent, the gears in the present construction have the bearings in the castings 58 surrounding the tube, these bearings, as shown at 60, being tapped into the casing 58 and receiving the shafts 62 which carry the gears 57. A more substantial bearing is thus provided than in the construction shown in the Letters Patent.

As in the construction shown in the Letters Patent, the gears 57 are connected to the reciprocating fingers 12 by connecting rods or pitmen 64 received upon crank pins 66 carried by reciprocating parts 12 of these fingers. As shown in Fig. 4, a simple construction of a crankpin suitable for this purpose comprises a cylindrical pin having an integral flange or head 68, and slotted in its lower part to embrace the finger, the pin also being drilled out in its upper part as

shown at 70, to receive an integral stud 72 formed upon the finger. A bushing 74 having a flange 76 at its lower end to bear upon the upper edge of the finger, is preferably inserted in the enlarged opening in the pitman which surrounds the crank pin 66.

As in the construction shown in the Letters Patent, the parts are preferably so arranged that opposed fingers will move together simultaneously and that successive pairs of fingers will operate in succession.

In Fig. 8 of the drawings is shown a modification of the tooth construction on the oscillating part of the picker finger which is designed to accomplish the same result or substantially the same result, as the guards 40 shown in Fig. 5 without appreciably diminishing the effectiveness of the picking action of the finger. In other words by broadening the ends of the teeth as shown in Fig. 8, the teeth will not be sharp enough to take hold of leaves, sticks and bolls, but will yet be sufficiently sharp to engage the fibre and pick them clean.

What I claim as new is—

1. In a cotton picker, a reciprocating picker finger having at its picking end a part adapted to oscillate, a weight having a positively limited lost motion connection with the reciprocating part of said finger permitting movement of said weight on said finger in the same direction at the end of the positive movement of the said weight by said finger, the cooperating stop surfaces on said weight and the reciprocating part of said finger by which the lost motion is positively limited being all located substantially in a straight line and in the line of reciprocation, and connections between the weight and the oscillating part of said finger whereby the aforesaid movement of said weight on said finger both effects and limits the oscillation of said oscillating part.

2. In a cotton picker, a reciprocating picker finger having at its picking end a part adapted to oscillate, said oscillating part comprising an arm in bell-crank relation to the picking end thereof and having a positively limited lost motion connection with the reciprocating part of said finger, the cooperating stop surfaces by which said lost motion is positively limited being substantially in a straight line and in the line of reciprocation of said reciprocating part, and a weight acting upon the bell-crank arm of said oscillating part and also having said positively limited lost motion connection with said reciprocating part whereby its inertia effects the oscillation of said oscillating part.

3. In a cotton picker, a reciprocating picker finger having at its picking end a part adapted to oscillate, a weight, connections between said weight and the reciprocating part of said finger comprising cooperating

stop surfaces on said weight and said finger arranged substantially in a straight line in the line of reciprocation to permit a limited movement of said weight on said finger in the same direction at the end of a positive movement of said weight by said finger in each direction of the reciprocating movement, and connections between the weight and the oscillating part of said finger whereby the aforesaid relative movement both effects and limits the oscillation of said part.

4. In a cotton picker, a reciprocating picker finger having at its picking end a part adapted to oscillate, a weight having substantially rectilinearly arranged in the line of reciprocation, a positively limited lost motion connection with the reciprocating part of said finger permitting movement of said weight on said finger in the same direction at the end of the positive movement of said weight by said finger, connections between the weight and the oscillating part of said finger whereby the aforesaid movement of said weight on said finger both effects and limits the oscillation of said oscillating part, and means confining said weight to a substantially rectilineal path of movement with and relatively to said finger.

5. In a cotton picker, a reciprocating picker finger having at its picking end an oscillating part carried thereby, a weight having substantially rectilinearly arranged in the line of reciprocation, a positively limited lost motion connection with the non-oscillating part of said finger whereby said weight may move relatively to said finger at the end of its positive movement thereby in each direction, a bell crank arm on said oscillating part through which the movement of said weight relative to said finger effects the oscillation of said oscillating part, and means for confining said weight to a substantially rectilineal path of movement.

6. In a cotton picker, a reciprocating picker finger comprising at its picking end a part adapted to oscillate a weight supported independently of the oscillating part of said finger for rectilineal movement and having a lost motion connection with said finger permitting a limited relative movement of said weight and finger at the end of the positive movement of said weight by said finger in each direction, and connections between the weight and the oscillating part of said finger whereby such relative movement effects the oscillation of said part.

7. In a cotton picker, a reciprocating picker finger comprising a rectilinearly movable part and an oscillating part pivotally connected to said first-mentioned part at the picking end, a weight having a limited lost motion connection with the rectilinearly movable part and engaging the oscillating part at a point at one side of its pivot

- whereby said weight operates through its inertia to effect the oscillation of said oscillating part at the end of each stroke of said reciprocating finger, and means independent 5 of said oscillating part for supporting and guiding said weight in a substantially rectilineal path throughout its movement.
8. In a cotton picker, a reciprocating picker finger comprising a substantially rectilineally movable part and a part pivoted 10 to said first-mentioned part near the picking end to have a limited oscillating movement thereon, and means for both effecting and limiting said oscillating movement, comprising a weight having a limited lost motion connection with said rectilineally reciprocating part and an operating connection to said oscillating part whereby its inertia effects the relative movement of said 15 parts at each end of the stroke of the reciprocating finger, and means for supporting said weight in such manner that it does not bear upon the pivotal connection between said parts.
- 20 9. In a cotton picker, a reciprocating toothed finger having an oscillating picking portion at its end and guards for the endmost teeth.
10. In a cotton picker, a reciprocating toothed finger having at its end guards for the endmost teeth.
11. In a cotton picker, a reciprocating toothed finger having an oscillating portion at its picking end and having adjacent to 25 the endmost teeth lateral wings guarding and restricting the action of said teeth to the fibre.
12. In a cotton picker, a reciprocating toothed finger having an oscillating portion 30 at its picking end, said oscillating portion being provided adjacent its endmost teeth with lateral guards projecting beyond the points of said teeth and laterally spaced therefrom sufficiently to permit said teeth 35 to act upon the cotton fibre without acting upon the leaves and other non-fibrous material with which said finger may come into contact.
13. In a cotton picker, a reciprocating finger having pivoted thereon a toothed oscillating part constituting its picking end, a weight on said oscillating part in bellcrank relation to the line of teeth on said part, and stops arranged to provide a lost motion connection between said weight and the reciprocating part of said finger, said stops being arranged in line in the line of reciprocation. 50
14. In a cotton picker, a reciprocating finger having pivoted thereon a toothed oscillating portion constituting the picking end of the finger, opposed spaced stops arranged in line in the line of reciprocation of said finger and at one side of said pivot, and an inertia member on said oscillating portion of the finger and movable therewith between said stops. 60
15. In a cotton picker, a reciprocating finger having pivoted thereon a toothed oscillating portion constituting the picking end of the finger, a weight carried by said oscillating portion in bellcrank relation to the teeth thereof, cooperating stops on said reciprocating and oscillating parts of said finger limiting the oscillating thereof, the 70 stops on said reciprocating part being in line with the rectilineal line of travel of said weight with said reciprocating part. 75
16. In a cotton picker, a reciprocating finger having one edge provided with teeth and having pivoted thereon a toothed oscillating portion constituting the picking end of said finger and providing a continuation of the toothed edge thereof, the opposite edge of said reciprocating finger being provided with stops arranged in line in the line of reciprocation, a weight on said oscillating portion arranged to travel therewith between said stops, and lateral guides supporting said weight and through said 80 weight the picking end of said finger during the reciprocating travel of said finger. 85

Signed at New York, N. Y. this 30th day of January 1923.

ROBERT L. McGEEHEE.
